[57] CLAIM

The ornamental design for wheel for a model car, as shown and described.

DESCRIPTION

FIG. 1 is a perspective view of a wheel for a model car showing my new design;

FIG. 2 is a front view thereof;

FIG. 3 is a rear view thereof;

FIG. 4 is a sectional view thereof taken along the lines 4—4 in FIG. 2;

FIG. 5 is a perspective view of a modified embodiment of the design shown in FIGS. 1-4;

FIG. 6 is a front view thereof;

FIG. 7 is a rear view thereof; and,

FIG. 8 is a sectional view thereof taken along the lines 8—8 in FIG. 6.

The broken lines shown in FIGS. 1,3,4,5,7 and 8 is for illustrative purposes only and forms no part of the claimed design.
